US00D656614S

(12) **United States Design Patent**
Stinson

(10) **Patent No.:** US D656,614 S
(45) **Date of Patent:** ** Mar. 27, 2012

(54) **DIGITAL RADIOPHGRAPHY (DR) IMAGER PROTECTOR**

(75) Inventor: **John Stinson**, Ann Arbor, MI (US)

(73) Assignee: **Clear Image Devices**, Ann Arbor, MI (US)

(**) Term: **14 Years**

(21) Appl. No.: **29/393,392**

(22) Filed: **Jun. 3, 2011**

(51) **LOC (9) Cl.** 24-01

(52) **U.S. Cl.** **D24/161**
